MECHANISM FOR CLOSING CARTON ENDS

Carl Wilhelm Hartmann, Lyngby, near Copenhagen, Denmark, assignor to Satona Limited, Edinburgh, Scotland

Application April 27, 1940, Serial No. 332,633
In Great Britain May 24, 1939

5 Claims. (Cl. 93—36.8)

This invention relates to improved mechanism for closing carton ends for use with machines for supplying empty cartons to treating (e. g. waxing or proofing) or filling stages on carton treating or filling machines. In such machines it is known to supply on to formers tubular cardboard or like members, pre-creased at their ends for folding into closed bases and upper ends, and the object of this invention is to provide means for effectively closing the pre-creased base ends of such cartons. The invention is useful in connection with square section cartons having what are known as "rosette" bases, each carton blank being brought to tubular form e. g. as described in co-pending application No. 332,030 and each

Fig. 4 is a detail side elevation view of the part of the machine relevant to the shaping of the rosette bases of the cartons and looking on the reverse side to that shown in Fig. 1.

Fig. 5 is a perspective view of the base end of a carton just before it is operated upon by the base closing means shown in Figs. 2 and 3.

Fig. 6 is an end elevation of a carton showing the base partially closed, and

Fig. 7 is a perspective view showing the carton base folded into rosette form and now ready for transfer to the stage where it will receive an adhesive sealing piece and be subjected to high pressure to firmly squeeze the folds into a flattened base.

Referring more particularly to Fig. 1 of the drawings the stack of cartons 1 is supported on the base 2 which has combined with it mechanism for initially distending each carton into tubular form, such means including a bar 4 which is engaged inside each flattened carton so as to locate one of the four walls of the square section carton firmly against the stack of cartons. Engaging the upper edge of the leading carton is a folding bar 5 which is carried across a pair of swinging arms 6 which traverse the folding bar into an arcuate path forwardly whilst still engaging the same edge of the carton, and the result of this is to nearly open the carton to square tubular section so that it has a parallelogram or rhomboid cross section. The movements imparted to the carton by the combination of the bar 4 and folding bar 5 prevents one corner of the carton to the space adjacent to the converging sides of two rollers (not shown) having roughened peripheries and which draw the carton between them and deliver it on to a shaping plate 9 provided with means for completing the square section configuration of each carton. The carton is now of tubular form and open at both ends, the end adapted to comprise the top being presented towards and in axial alignment with one of a number of formers 12 of square section radiating symmetrically from a rotary support 13.

At this stage the tubular carton is pressed on to the aligned former 12, this being effected by means of a slide 14 which is shown in Fig. 1, and moved in unison with the bar 4, and carries a finger-piece 15 adapted to engage over one edge of the open base of the carton and to press the carton on to the appropriate former 12.

By the foregoing means all of the formers 12 can be fitted with cartons and each former carries its carton through stages appropriate to

In an embodiment of the invention a former is provided adapted to receive a carton, and is adapted to be opposed to a head carrying a number of relatively translatively movable carton base engaging and closing members all located wholly uni-laterally in relation to planes radiating from a common centre approximating to the predetermined location of the centre of the base of each carton operated upon, and having side faces very close to or in said planes so as to radiate from or to be tangential with respect to a central zone of pressing operation of the head, and also all adapted to be pressed against the exposed base end of a carton and to be moved simultaneously inwards relatively to the head in tangential direction whilst in engagement with the base end parts of the carton.

In order that this invention may be clearly understood and readily carried into effect drawings are appended hereto illustrating an embodiment thereof as applied to square section tubular cartons of the type already referred to, and wherein:

Fig. 1 is a diagrammatic side elevation view of a carton base closing stage of an apparatus for converting carton tubular blanks into sealed base cartons.

Figs. 2 and 3 are sectional elevation and plan views respectively of the means for engaging and forming the rosette bases of the cartons when the cartons are fitted on formers.

sealing the base of the carton and thereupon delivering each carton on to a conveyor 16.

A convenient arrangement of formers is the octagonal form shown in Fig. 1, this affording eight stages the first of which is already described. The rotary structure carrying the formers travels in the direction of the arrow and is moved intermittently by any suitable mechanism such as e. g. a Maltese cross member 17 on the shaft of the rotary member 13 and the customary rotary member engaging successively in the radiating slots of the Maltese cross member. The second stage with the formers is to fold inwards the sections comprising the base of the carton, these sections being suitably creased so that when folded inwards they form a rosette base on the carton. The mechanism for forming this rosette base is shown in Figs. 2 and 3, and comprises a head 18 carrying four members hereinafter described, adapted to be moved translatively relatively to the head 18 simultaneously with the sliding movement of the head 18 radially towards the appropriate former.

Following the base-shaping stage each former carries its carton into two further stages consisting of radially reciprocated presser members 19 and 20 which are suitably heated and are urged against the opposed free end of the appropriate former so as to firmly press the rosette base into a flat condition. When the rosette base of each carton is flattened as above described, a sealing disc or label is applied thereover at the stage 27, and this sealing disc is coated with a suitable adhesive and pressed against the appropriate carton base. The mechanism for carrying out this operation is more clearly described in a co-pending application.

Referring again to Fig. 7 it will be seen that the base of the carton is folded into four trapezoidal sections 1a, 1b, 1c, 1d on diagonal creases 1e, and the lower or horizontal corner creases 1f of the sides of the cartons. The action of folding the base sections on the diagonal creases 1e and the lower corners 1f of the sides of the body part produces four treble thickness parts 1g and four single thickness parts 1h in the base.

The base of the carton can be regarded as a rosette base, and the means for producing this rosette base is more clearly illustrated in Figs. 2 and 3 in which the head 18 has an annular plate 83 with a square opening 81 in which is engaged the base end of the carton on the appropriate former 12, by reason of the head 18 being depressed through a guide 18b fixed to a frame 13a supporting the formers 12, the arrangement being that when the base is closed it lies in the plane of the inner face of the plate 83. This depression is effected by the reciprocation of a rod 18c actuated intermittently from a part of the machine and connected to the head 18 by a crank 18d and link 18e. The folding of the four creased sections of the base forming the rosette base is effected by the inward radial movement of four presser blocks 82 arranged between the flanged base 18a of the head 18 and the plate 83 fixed in relation to the plate 18a by bolts 84. The presser blocks 82 are of substantially square section and each has one side face 82a longer than the side face 82b parallel therewith to afford an inclined leading end 82c (see Fig. 3). The sides 82a are substantially radial in relation to the axis of the presser head or, as is preferred, are very narrowly spaced away from but parallel with planes radiating from the cen-

tre of the opening 81 so as to be tangential with respect to a very small imaginary circle at the centre of the opening 81. Also the leading ends 82c are inclined downwardly and rearwardly into arcuate corners 82e. It will be seen that the ends 82c which engage the creased base sections of the carton are inclined in two dimensions.

It will be apparent that all of the blocks 82 are located wholly uni-laterally in relation to planes radiating from a common centre approximating to the predetermined location of the centre of the base of each carton operated upon in the square opening 81, and that such blocks 82 have side faces 82a very close to or in said radiating planes so as to radiate from or to be tangential with respect to a central zone of pressing operation of the head and also all adapted to be pressed against the exposed base end of a carton and to be moved simultaneously inwards 20 relatively to the head in tangential directions whilst in engagement with the base end of parts of the carton.

When the blocks 82 are urged simultaneously towards the centre of the press head the creased base sections will be folded flat, the arcuate corners 82e ensuring a smooth pressing and sliding action.

By reference to Figs. 5, 6 and 7 it will be seen how the carton 1 has its fully open base shown in Fig. 5, gradually closed as e. g. in Fig. 6 towards the rosetted form shown in Fig. 7.

The presser blocks 82 are actuated by four bell crank levers 85 rotating on pivot pins 86 and each having the limb of one roller 87 sliding in a transverse channel 82f in each block 82. The other end of each lever carries a roller 88 engaging in a radial slot 89 in an annular ring 90 which is oscillated through the angle appropriate to the operation of the levers 85 by a toothed segment 91 engaging a toothed segment 90a on the ring 90. The toothed segment 91 is carried by the upper end of an inclined shaft 91a, the lower end of which carries a crank 91b having a roller 91c engaging in a cam grooved roller 92.

I claim:

1. Mechanism for forming a closed rosette base end on tubular cartons comprising a head, a former adapted to receive a carton to be opposed to said head, a number of relatively translatively movable carton base engaging and closing members carried by said head and all located wholly uni-laterally in relation to planes radiating from a common centre approximating to the predetermined location of the centre of the base of each carton operated upon, side faces on said members very close to said planes so as to radiate from or to be tangential with respect to a central zone of pressing operation of the head, and also all adapted to be pressed against the exposed base end of a carton and to be moved simultaneously inwards relatively to the head in tangential directions whilst in engagement with the base end parts of the carton.

2. Mechanism for forming a closed rosette base end on tubular cartons comprising formers on to which the cartons are adapted to be delivered with their open base ends directed beyond the ends of the formers, a head adapted to be pressed against each such end of each former, four presser blocks slideable across said head each with one side substantially radial in relation to the centre of the head and with a carton base engaging face uni-lateral in relation to said radial side, each block having an inner or leading end which is inclined in two dimensions to engage the carton

bases, and operating means common to all of said blocks adapted to reciprocate the blocks to effect said sliding action.

3. Mechanism for forming a closed rosette base end on tubular cartons comprising formers on to which the cartons are adapted to be delivered with their open base ends directed beyond the ends of the formers, a head adapted to be pressed against each such end of each former, four presser blocks slideable across said head each with one side substantially radial in relation to the centre of the head and with a carton base engaging face uni-lateral in relation to said radial side, each block having an inner or leading end which is inclined in two dimensions to engage the carton bases, operating means common to all of said blocks adapted to reciprocate the blocks to effect said sliding action, said operating means comprising a number of bell crank levers mounted for oscillation in said head and each having one limb in driving engagement with one of said blocks, an oscillatable actuating member common to said levers, the other limbs of the levers having driving engagement with said oscillatable member.

4. Mechanism for forming a closed rosette base end on tubular cartons comprising formers on to which the cartons are adapted to be delivered with their open base ends directed beyond the ends of the formers, a head adapted to be pressed against each such end of each former, four presser blocks of substantially rectangular cross section slideable across said head each with one side substantially radial in relation to the centre of the head and with a carton base engaging face

5 10 15 20 25 30 35

uni-lateral in relation to said radial side, each block having an inner or leading end which is inclined in two dimensions to engage the carton bases, a plate located over said sliding blocks and formed with a rectangular opening to receive the carton base, and operating means common to all of said blocks adapted to reciprocate the blocks to effect said sliding action.

5. Mechanism for forming a closed rosette base end on tubular cartons comprising formers on to which the cartons are adapted to be delivered with their open base ends directed beyond the ends of the formers, a head adapted to be pressed against each such end of each former, four presser blocks of substantially rectangular cross section slideable across said head each with one side substantially radial in relation to the centre of the head and with a carton base engaging face uni-lateral in relation to said radial side, each block having an inner or leading end which is inclined in two dimensions to engage the carton bases, a plate located over said sliding blocks and formed with a rectangular opening to receive the carton base, operating means common to all of said blocks adapted to reciprocate the blocks to effect said sliding action, said operating means comprising a number of bell crank levers mounted for oscillation in said head and each having one limb in driving engagement with one of said blocks, an oscillatable actuating member common to said levers, the other limbs of the levers having driving engagement with said oscillatable member.

CARL WILHELM HARTMANN.
